Edward J. Donnan & Charles Dufree
Sewing Patent

The scheme referred to in the above Sewing Patent and making part
of the same containing a description of the novel and said Ed
ward J. Donnan and Charles Dufree themselves of this impo
-tinent in the manufacturing of rope.

This Machine is composed of a shaft or reel and in place of a
wheel or crank to give the twist or turn for laying. Strands or rope
or that a strand or rope can be twisted or laid in certain lengths
at a time while a rope or strand is twisted or laid of any
required length. The shaft to be fixed to a reel or proper sup
-port in boxes or gunwales and made of proper materials with a
hole passing into the side incident at the end so that when a rope
or strand is wound on the shaft the end of it can pass through the
eye hole made in the end of the shaft not interfering with its
support thus giving a chance for spinning to it another length
of yarn. Then the shaft being turned gives the turn for the lay
ing of strands or rope, which when laid is again to be twisted
leaving the rope out as before then on laying and spinning until
any required length is finished. The chief object is to make a
rope of any appropriate length in one piece by laying it in portions
of convenient length and spinning into the ends of the end of each
part as is already laid. In laying several ropes into larger, or bound
yarn into a rope the novel machine must be equal to the num
ber of strands and rope and may remain stationary or be placed
on slides or truck wheels as may be necessary.
